CLARENCE J. LEMONT, OF SOUTH MILWAUKEE, WISCONSIN, ASSIGNOR, BY MESNE ASSIGNMENTS, TO LINE MATERIAL COMPANY, OF SOUTH MILWAUKEE, WISCONSIN, A CORPORATION OF DELAWARE

LIGHTING FIXTURE

Application filed November 15, 1928. Serial No. 319,582.

This invention relates to certain new and useful improvements in lighting fixtures and refers more particularly to a clip for cushioning and holding the reflectors at their 5 points of connection with the body of a lighting fixture.

Reflectors for street lighting fixtures are usually stamped from sheet metal and have their lower or reflecting side coated with 10 vitreous enamel which is extremely hard and brittle. Due to the brittle nature of the enamel coating, it has always been difficult to provide means for attaching the reflectors to the lighting fixtures without chipping and 15 cracking and the present invention has as an object to provide an efficient and simple cushioning means for protecting the reflector at its point of connection with the fixture.

Another object of this invention resides 20 in the provision of a simplified cushioning member for use in fastening reflectors to lighting fixtures which is formed of lead or other suitable soft material.

A further object of this invention resides 25 in the provision of an improved cushioning device for protecting reflectors at their point of connection with a lighting fixture which is inexpensive and which may be readily applied at the time of assembly.

30 And a still further object of this invention resides in the provision of an improved cushioning member for reflectors of lighting fixtures which incorporates means for locking the securing means against accidental detachment.

With the above and other objects in view which will appear as the description proceeds, my invention resides in the novel construction, combination and arrangement of parts 40 substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of my invention constructed 45 according to the best mode I have so far de-

vised for the practical application of the principles thereof, and in which:

Figure 1 is a view, partly in elevation and partly in section, of a lighting fixture illustrating my improved manner of connecting 55 the reflector with the fixture;

Figure 2 is a bottom view of the device with part of the reflector broken away;

Figure 3 is an enlarged, fragmentary, sectional view taken through Figure 2 on the 60 plane of the line 3—3, and

Figure 4 is a perspective view of one of the cushioning members shown detached from the reflector.

Referring now more particularly to the 65 accompanying drawing, the numeral 5 designates the body of a lighting fixture which is usually formed of porcelain or the like, having a suspension member or eye 6 by which the device is suitably supported and 70 being recessed to receive a lamp socket and its adjusting means, not shown.

Numerous different methods of reflecting the light are used and in the present invention the light of the lamp, not shown, is reflected by a reflector member 7 of substantially disc shaped and stamped from sheet metal. The under or reflecting side of the reflector is coated with a vitreous enamel to give the desired reflecting surface; and to 75 protect the enamel which is extremely hard and brittle, from cracking and chipping when applied to the fixture this invention provides a new and novel cushioning member 8 formed of a strip of soft metal, such as lead 80 or the like.

The cushioning members 8 are provided at each point of connection of the reflector with the body and are each folded at a medial point to form an upper leg 9 and a lower leg 90 10, and in the present embodiment the legs 9 and 10 have their outer ends enlarged, as at 11 and 12, and apertured, as at 13 and 14, respectively. The metal adjacent the aperture 14 in the lower arm 10 is pressed upwardly in an annular bead 15 and the aperture 13 in the upper leg 9 is of a size sufficient to receive the annular bead. In use, the cushioning members are slipped over the flanged periphery 16 of the central opening in the 95 100

reflector and positioned one adjacent each opening 17, the lower arms 10 being pressed upwardly to engage their annular beads 15 in the adjacent openings 17. The annular beads 15 are of sufficient height to extend through the openings 17 and likewise through the apertures 13 in the upper arms 9 and thus completely protect the enameled surface of the reflector.

10 Attaching screws 18 preferably having a squared head 19 pass through the aligned openings in the cushioning members and the reflector to be threaded in metallic sleeves 20 cemented or otherwise secured in apertures 21 formed in the wall of the procelain 15 housing or body 5 and to prevent the sharp edges 19 from digging into the soft metal of the cushioning members, washers 22 which are preferably formed of relatively thin metal 20 to prevent localized pressure on the reflector are provided between the heads of the screws and the cushioning members. As lighting fixtures of this character are more or less subject to vibration in many different forms, 25 means are provided for preventing retrograde turning of the screws 18 and the consequent dropping of the reflector, which consists of a lip or lug 23 on the extreme outer 30 end of the lower arm 10 of each cushioning member which, after the screws have been drawn tight, is bent downwardly to engage the adjacent flat face of the head 19 of its screw.

From the foregoing description, taken in 35 connection with the accompanying drawing, it will be readily apparent to those skilled in the art to which an invention of the character described appertains that I provide a new and novel cushioning means for protecting 40 the enameled surface of reflectors of lighting fixtures at their points of connection with the fixture which means are extremely simple and inexpensive and which likewise form locking members for preventing accidental 45 detachment of the holding screws of the reflector.

What I claim as my invention is:

1. The combination with a lighting fixture having a body member and a reflector, of 50 means for connecting the reflector with the body member of the fixture, comprising a cushioning member adapted to be engaged over one edge of the reflector, and securing means passing through aligned apertures in 55 the reflector and cushioning member and engaged with the body of the fixture.

2. The combination with a lighting fixture having a body member and a reflector, of 60 means for connecting the reflector with the body member of the fixture, comprising clips formed of relatively soft material adapted to be engaged over one edge of the reflector and having a part disposed on each side thereof, and securing means passed through 65 aligned apertures in the reflector and clip

and engaged with the body of the fixture.

3. In a lighting fixture having a body member and a reflector adapted to be connected therewith, a device for protecting the reflector at its points of connection with the body member, comprising a clip formed of suitably soft material bent medially to have a part disposed on each side of the reflector, screw means passed through aligned apertures in the reflector and the clip and threaded 75 in the body, and means carried by the clip for preventing accidental turning of the screw.

4. A clip for protecting the enameled surface of reflectors of lighting fixtures at their 80 points of connection therewith, comprising a member formed of suitably soft material folded at a medial point to provide a pair of arms apertured adjacent their outer ends, one of said arms having a portion struck therefrom to be engaged in an aperture formed in the reflector when the clip is assembled therewith.

5. The combination with a lighting fixture having a body member and a reflector adapted 90 to be attached to the body member, the reflector having an aperture, of a cushioning clip formed of suitable soft material and folded medially to provide a pair of arms, the arms being apertured adjacent their outer 95 ends, an annular bead struck up from one of the arms adjacent its aperture which is received in the reflector aperture when the clip is assembled therewith, screw attaching means passed through the apertures in the 100 clip and reflector and threaded in the body member, and a lip carried by the clip and engageable with the head of the screw attaching means to prevent accidental turning thereof.

6. The combination with a lighting fixture having a body and a reflector connectible therewith, of a cushioning member to protect the reflector at its point of connection with the body member said cushioning member having a part engageable with one edge of the reflector to hold the same against movement with respect to the reflector, and securing means clamping the reflector to the body 110 through the cushioning member.

7. The combination with a lighting fixture having a body member and a reflector connectible therewith, the reflector having an aperture, of a cushioning member having a 120 part disposed on each side of the reflector with a part extended into the aperture to line the same and a part engaging one edge of the reflector to hold the cushioning member against turning about the axis of the 125 aperture, and screw means passing through the aperture and threaded into the body member to clamp the reflector to the body member through the cushioning member.

8. The combination with a lighting fixture 130

having a body member and a reflector connectible therewith, the reflector having an aperture, of a cushioning member having a part disposed on each side of the reflector 5 with a part extended into the aperture to line the same and a part engaging one edge of the reflector to hold the cushioning member against turning about the axis of the aperture, screw means passing through the 10 aperture and threaded into the body member to clamp the reflector to the body member through the cushioning member, and means carried by the cushioning member and engageable with the screw means to prevent 15 accidental turning thereof.

In testimony whereof I have hereunto affixed my signature.

CLARENCE J. LEMONT.
